UNITED STATES PATENT OFFICE.

HENRY R. POPE, OF FRANKLIN, PENNSYLVANIA.

TIME-LIMIT INDICATOR.

1,198,658.

Specification of Letters Patent. Patented Sept. 19, 1916.

Application filed March 28, 1916. Serial No. 87,380.

To all whom it may concern:

Be it known that I, HENRY R. POPE, citizen of the United States, residing at Franklin, in the county of Venango and State of Pennsylvania, have invented certain new and useful Improvements in Time-Limit Indicators, of which the following is a specification.

My invention relates to an improved time-limit indicator, which is adapted for various purposes, but is here shown and described as being applied to telephone service, for which it is especially adapted.

The object, construction and utility of my improved time-limit indicator, when applied to the use above stated, are herein set forth with sufficient clearness to enable those skilled in the art of telephone construction and operation, to make and use the same.

In the operation of nearly all telephone systems, it is customary to impose a specific time limit per message for the use of certain lines, and in such cases it is desirable to have some device which will automatically apprise the operator when such limit of time has been reached, so that the line may be disconnected.

It is, therefore, the object of this invention to provide a device which may be interposed in the lines of a telephone system, which will be automatically set in operation by the connection of the lines for use,—that is when the operator inserts the plug in the jack—and which will, at the expiration of a certain pre-determined limit of time, cause either an audible or visual indication to be set up, and whereby the operator will be informed that the line has been in use for the allotted period of time.

In the drawings which form a part hereof, I have shown a preferred form and a modified form of construction whereby I attain said object.

The various figures of said drawings are as follows:

Figure 1 is a transverse section of said device on line 1—1 of Fig. 2. Fig. 2 is a front elevation of same. Fig. 3 is a detail. Figs. 4 and 5 show a modified form of construction. Fig. 6 is a diagram illustrating one way in which my device may be connected into a telephone system.

The construction shown in Figs. 1, 2, 3 and 6 is substantially as follows: Within one of the circuits of a telephone, and located in the central office, in proximity to

the operator's position, is interposed any suitable indicative device which is adapted to manifest either an audible or a visual signal, and which is shown in the drawings as 60 a lamp 1, Fig. 6. Also in the signal circuit is interposed a suitable automatic switch 2, which is adapted, upon making suitable contact with a coöperating element, to close said circuit, whereby the indicative device 65 is energized and caused to produce the desired signal. Said element 2, which I term the traveler, or traveling terminal, is shown in elevation in Fig. 3, is adapted and arranged to close the signal circuit at the expiration of the limit of time which is prescribed for the use of the respective line with which it is associated, and, by such closing of said circuit to energize the indicative means, whereby the operator is informed that the line may be disconnected. The mechanism whereby said traveling terminal is actuated comprises a continuously-revolving shaft 3, which revolves in the direction indicated by the arrow. To said 70 shaft 3 is connected a suitable train of clock-work shown especially in Fig. 1, the gear 4 of which is operably or rigidly mounted upon the shaft 3. Said train of clock work is so constructed that said shaft 3 revolves 75 at a slow rate of speed, preferably about the same speed as that of the shaft upon which the hour-hand of an ordinary clock is mounted. The traveling terminal 2 is loosely mounted upon said shaft 3 and is 80 magnetically retained in its normal, open-circuit position as shown in Fig. 1 by means of the magnet 5. Said terminal is provided with a resilient friction element 6, the upper 85 end of which is secured to said traveler in 90 any suitable way, and the lower end thereof bears against said shaft and the amount of friction which is caused between said element 6 and said shaft 3 is regulated by 95 means of the screw 7; such friction is never 100 sufficient, however, to overcome the magnetic attraction of the coil 5, when said coil or magnet is energized. One pole of any suitable source of electrical current is connected, by means of a suitable conductor, to 105 said shaft 3, which is grounded. In proximity to the upper, free end of said traveling electrode 2 is located an adjustable terminal 8, to which the other pole of said electrical source is connected.

The indicative means 1, may, in a telephone system, be interposed in either the

line circuit or in the cord circuit, but it is here shown as being interposed in the line circuit and its connections are such that, when the operator inserts the plugs in the 5 jack to place the line in service, the magnet 5 is thereby automatically deenergized, which causes it to release said terminal 2, which thereupon becomes free to move with said shaft 3 upon which it is mounted, and 10 it does so move until the upper end thereof comes into contact with the adjacent end of the terminal 8; this completes the signal circuit, energizes the indicative device, and informs the operator that the prescribed limit 15 of time has elapsed.

By the longitudinal adjustability of the terminal 8, whereby the intervening space between the contact point of same and the terminal 2 may be varied, the time limit 20 may be varied, either shortened or lengthened, as desired.

When the line is disconnected, the removal of the plug from the jack automatically reestablishes a current through the 25 magnet 5, and the traveler or terminal 2 is drawn by the resulting magnetic attraction to its normal, open-circuit position.

Several terminals 2 may be mounted upon the same shaft 3, as shown in Fig. 2, and 30 when this is done, it may be found to be desirable to mount a drum 9 upon said shaft, about which, a weight-cord 10 may be wound, having a weight 11 attached thereto, the action of which will be to assist the 35 clock work to overcome the frictional resistance of the terminals 2 when they are in a stationary condition, at either open or closed circuit.

In Figs. 4 and 5 I have shown a modified 40 form of construction for holding and releasing the terminal 2. This comprises a solenoid 12, the plungers 13 of which normally, and when the coil of said solenoid is not energized, rests upon the foot 14 of 45 said terminal and retains the same in the position shown in Fig. 4. When the solenoid becomes energized, by placing the plug within the jack, the plunger 13 is magnetically raised to and retained in the position 50 shown in Fig. 5 and this will permit said terminal 2 to move with the shaft 3 upon which it is mounted, and it does so move until the upper end comes into contact with the terminal 8, thereby closing the signal 55 circuit.

When the operator removes the plug from the jack to disconnect the line with which the signal coöperates, this also automatically cuts out the solenoid, and deenergizes the 60 same, which permits the plunger 13 to fall upon the foot 14 which restores the terminal to its open-circuit position. This construction will require a slight re-arrangement of the signal circuit incident to energizing the 65 release device, instead of reenergizing same

to cause its release of the terminal, but such changes as this may require, will be readily perceived and made by those skilled in the art of electrical construction and wiring.

From the foregoing description, it may be 70 readily understood that this indicator is not a "busy" indicator which is in the indicative condition throughout the time that the line with which it is associated, is busy, but on the contrary, it becomes in the in- 75 dicative condition only at the instant when the limit of time has been reached, thereby apprising the operator at precisely the time when the line should be disconnected, in order that the use of said line may not ex- 80 ceed the prescribed limit of time.

As previously stated, in Fig. 6 I have shown the indicative device 1 as being interposed in the line circuit, but I do not wish to be understood as confining the 85 location of same to such position, as it could with equal facility be interposed in the cord circuit, and, as a matter of fact, when many lines are to be equipped with my device, it will be preferable, for various reasons, read- 90 ily apparent to those skilled in the art, to interpose said indicative device in the cord circuit; such a transposition would neces- 95 sitate a slight change in the wiring and some of the accessories, but these changes will be readily perceived and made by any skilled electrician.

There are many other purposes for which my improved time-limit indicator may be used in addition to telephone service, and, 100 in fact it may be advantageously employed wherever certain pre-determined periods of time are to be observed, such as photographic exposure, printing and development, recitation periods in schools, etc. 105

I claim the following:

A time-limit indicator, comprising, in combination, a source of electrical current, a conductor connected to one of the poles of said source, a conductor connected to the other pole of said source, a stationary terminal to which one of said conductors is connected, a movable terminal to which the other of said conductors is connected, said movable terminal being arranged to be moved into contact with said stationary terminal so as to form an electrical circuit, a continuously-moving element by which said movable electrode is carried and by which it is adapted to be moved, at a certain pre-determined rate of speed from a normal, open-circuit position to said closed-circuit position, releasable means adapted to detain said movable terminal at its open-circuit position and to release the same as required 110 115 120 125 130 whereby it becomes free to be moved by said continuously-moving element into said closed-circuit position, the travel of said movable terminal being such as to define a pre-determined interval of time, means

adapted to vary said interval as desired, an indicative device interposed in one of said conductors adapted to indicate the closing of said circuit, and means adapted to restore said movable terminal to its normal, open-circuit position.

In testimony whereof I affix my signature in presence of two witnesses.

HENRY R. POPE.
